UNITED STATES PATENT OFFICE

STANLEY T. BROCKWAY, OF AUBURN, INDIANA

MECHANICAL TOY

Application filed May 2, 1930. Serial No. 449,179.

This invention relates to improvements in mechanical toys of that type in which movement is imparted to configurations of living beings by power derived from the action of wheels that roll upon the ground and which afford support for said configurations.

An illustrative embodiment of the invention is shown in the accompanying drawing in which is characterized a dog in pursuit of a rabbit, and in which mechanism is shown whereby lifelike movements are imparted to the configurations from the ground wheels:

Fig. 1 is a plan view of a form of the invention;

Fig. 2 is a side elevation projected from Fig. 1;

Fig. 3 is a detail showing the crank-shaft for one pair of the ground-wheels, the frame in which the shaft is mounted, and the pitman for actuating one of the configurations;

Fig. 4 is a detail view, in cross section showing one of the configurations and the operating mechanism therefor; and

Figs. 5, 6, 7 and 8 are side elevations illustrating respectively the successive stages in the movement of the other configuration which are sequential to the position of the same configuration shown in Fig. 2.

In the illustrative embodiment there is shown a carriage frame 1 mounted upon axles 2 and 3 that are provided at their outer ends correspondingly with wheels 4-5 upon which the carriage may be propelled upon the ground.

The rear end of the frame 1 is bifurcated, each arm 6 being provided with an upright 7 having forwardly and rearwardly extending branches 8 and 9 which constitute a support for one of the configurations, such as of a dog. Said configuration consists of a body

portion 10 having pivoted therein fore and rear legs 11 and 12 respectively, the pivots being indicated by 13 and 14 upon which said legs have hinged movement. The forelegs 40 have pivots 15 that extend through slots 16 made in the forwardly extending branches 8 on the uprights 7 in which they have play in the direction of said slots to an extent limited by the lengths of said slots. The rear legs 45 have pivotal connections respectively with

the rearwardly extending branches 9 on the uprights 7 as indicated by 17, said pivots being loosely fitted in the legs or the branches so as to afford limited play relatively between said legs and branches aside from the axial movement of said legs with respect to the axis of said pivots. Said rearwardly extending branches 9 are each provided with a shoulder or point 18 that has contact with the pivot 14 that connects the rear legs with the body 10 so as to retard movement of said pivot 14 in its movement about the axis of the pivotal connections 17.

The axle 2 has formed therein a center crank 19, and on said crank is connected at one of its ends a link 20. The opposite end of the link is pivotally connected with the body 10 as indicated by 21, so that as the axle 2 is rotated, vertical reciprocating movement is thereby imparted to said body.

The axle 3 also has formed therein a center crank 22 upon which is mounted a pendant extension 23 on the body 24 of another configuration, as of a rabbit. Said body 24 and its extension 23 are integral and move pivotally upon the crank 22. The forward end of the carriage frame 1 is bifurcated, and the extension 23 is disposed between the arms 25, and in said arms are transversely secured a pair of pins 26-26' spaced apart and which extend in a plane above the axle 3 across the path of the pendant extension 23. The spacing between said pins is such as to permit limited play of said extension therebetween. The rear face of the pendant 23 has an irregular surface including an outwardly extending shoulder or point 27 that has contact with the pin 26 during the cycle of movement of said extension causing accelerated movement to be imparted to the body 24.

When the carriage is drawn or propelled upon the ground the configurations are actuated. The body 10 is moved upwardly by the link 20 during the upward throw of the crank 20, and during the first portion of its upward movement the body swings upon the pivot 14. During the latter portion of the upward throw of the crank 19, the body 10 tilts upon the pivotal connection 21 with the link so that the rear end of the body is elevated and the

pivot 14 is moved over the shoulders 18 against which said pivot bears momentarily. During the downward throw of the crank 19 the body 10 is tilted upon the axis of the pivot 14 during the first portion of the downward throw, while the rear end of the body is detained in elevated position through interference of the shoulders 18 with the pivot 14. As the downward throw of the crank 19 is completed the body 10 tilts upon the pivotal connection 21, which movement is accentuated when the pivot 14 slips from contact with the shoulders 18 permitting the rear end of the body to fall. During the cycle of action of the body 10, the front and rear legs 11 and 12 are oscillated upon the axes of their pivotal connections 15 and 17 respectively so that the legs are first extended outwardly in opposite directions and subsequently swung inwardly to the point of commencement. In this manner the configuration formed by the body 10 and legs 11-12 characterizes the lifelike action of an animal in pursuit.

During the upward throw of the crank 22, the irregular surface on the extension 23 of the body 24 is stroked against the rearmost pin 26' which causes the body 24 to pitch forwardly until the extension has contact with the foremost pin 26, and during the downward throw of the crank 22 the thrust of the extension against the foremost pin 26 causes the body 24 to react and swing rearwardly upon the axis of the crank to the position at the commencement of its cycle of movement. The action thus imparted to the configuration, consisting of the body 24 and its extension, characterizes the lifelike action of an animal pursued.

Claims:

- 40 1. A mechanical toy comprising a carriage frame; an axle supporting said frame provided with a center crank, said frame having uprights provided with rearwardly and forwardly extending branches, said rearwardly extending branches having shoulders, and said forwardly extending branches having elongated slots therein; a configuration having a body and fore and rear legs pivoted therein, the pivot connecting said rear legs and body being engageable by said shoulders; pivotal connections between said rear legs and the corresponding branches on said upright at points spaced from the pivot connecting said rear legs and said body; pivotal connections between said forelegs and the corresponding branches on said upright which connections have sliding movement in said slots; and a link on said center crank imparting movement to said body.
- 45 2. In a mechanical toy, a wheeled frame; a configuration having a body and fore and rear legs pivoted therein; pivotal connections between said rear legs and the frame at points spaced from the pivot connecting said rear legs and said body; shoulders on said

frame having momentary engagement with the pivot connecting said rear legs and body; pivotal connections between said forelegs and said frame at points spaced from the pivot connecting said forelegs and body, there being elongated slots in the frame in which said connections have sliding movement; and means operatively relating the wheels with the frame and said body.

3. In a mechanical toy, a wheeled frame; a configuration having a body operatively related with the wheels for said frame; fore and rear legs pivoted in said body, said rear legs being pivoted on said frame at points spaced from the pivot connecting said rear legs with said body, said forelegs having at points spaced from their pivotal connections with said body sliding connections with said frame; and means on said frame momentarily engageable with the pivot connecting said rear legs and body.

4. In a mechanical toy, a wheeled frame; a configuration having a body operatively related with the wheels for said frame; and fore and rear legs pivoted in said body, said rear legs being pivoted on said frame at points spaced from the pivot connecting said rear legs with said body, said forelegs having at points spaced from their pivotal connections with said body sliding connections with said frame.

5. In a mechanical toy, a frame; an axle supporting said frame and having wheels thereon and a center crank; a configuration having an integral extension pivoted on said crank; and a pair of spaced apart pins positioned in said frame in a plane above said axle and between which said extension has limited play.

6. In a mechanical toy, a wheeled frame; a configuration related with the wheels of said frame so as to receive movement therefrom; a pair of spaced pins in the frame adapted to limit movement of said configuration; and a surface carried by said configuration and having engagement with one of said pins whereby movement of said configuration is accentuated.

In testimony whereof I affix my signature.
STANLEY T. BROCKWAY.
